UNITED STATES PATENT OFFICE.

EDWIN R. PENNEBAKER, OF ROME, GEORGIA.

SAFETY ATTACHMENT FOR WATCH-POCKETS.

1,030,488.

Specification of Letters Patent. Patented June 25, 1912.

Application filed December 3, 1910. Serial No. 595,444.

To all whom it may concern:

Be it known that I, EDWIN R. PENNEBAKER, a citizen of the United States, residing at Rome, in the county of Floyd and 5 State of Georgia, have invented new and useful Improvements in Safety Attachments for Watch-Pockets, of which the following is a specification.

This invention relates to safety attachments for watch pockets and the object of 10 the invention is the provision of a simple, efficient and readily applied device which will effectually hold and prevent accidental disengagement of the watch from the 15 pocket.

A further object of the invention is the provision of means for guiding the watch into the holder and for causing said guiding means to retain the device within the 20 pocket.

Further objects of the invention will appear as the following specific description is read in connection with the accompanying drawing which forms a part of this application, and in which:

Figure 1 is a horizontal section taken through a garment pocket showing the device applied. Fig. 2 is a vertical sectional view. Fig. 3 is a perspective view of the 30 device removed from the pocket.

Referring more particularly to the drawing 1 represents the pocket of the garment which is provided with button holes or 35 suitable reinforced apertures 2 in its sides adjacent the upper end thereof. Mounted in the pocket is the holding attachment

which comprises an approximately circular spring clip 3 having its upper ends laterally extended to form guides 4 and its sides provided with inwardly extending retaining fingers 5. The upper ends are provided with curved extremities 6 which enter the apertures 2 in the pocket and prevent the removal of the clip therefrom. They also serve as guides which render the insertion 45 of the watch into the clip relatively easy. I preferably line the clip and the fingers with some suitable material such as velvet or chamois so that the watch will not be scarred in placing the same in the clip or 50 removing the same therefrom.

Having thus described the invention, what is claimed is—

In a device of the class described, a substantially U-shaped unitary spring clip 55 adapted to be mounted in a pocket, a plurality of pairs of laterally and inwardly projecting fingers on opposite sides of the clip adapted to prevent lateral displacement of an article from the clip, longitudinally and outwardly extending fingers adapted to pass through the walls of a pocket to prevent accidental displacement 60 of the clip from said pocket, and a cushioning lining secured on the inner surface 65 of the clip and fingers.

In testimony whereof I affix my signature in presence of two witnesses.

EDWIN R. PENNEBAKER.
